(57) **CLAIM**

The ornamental design for a cover for seat belt buckle, as shown and described.

DESCRIPTION

FIGS. 1–5 illustrate a preferred embodiment of the cover for a seat belt buckle in which:

FIG. 1 is a side elevation view,
FIG. 2 is a rear end elevation view,
FIG. 3 is a front elevation view,
FIG. 4 is a top plan view, and
FIG. 5 is a bottom plan view.

FIGS. 6–10 illustrate another preferred embodiment of the cover for a seat belt buckle in which:

FIG. 6 is a side elevation view,
FIG. 7 is a rear end elevation view,
FIG. 8 is a front elevation view,
FIG. 9 is a top plan view, and
FIG. 10 is a bottom plan view; and,
FIG. 11 is a top plan view of the embodiment of FIGS. 1–5, together with portions of an automobile seat belt strap and buckle shown in phantom lines to illustrate the environment in which the invention is used, and not part of the present invention.
